UNITED STATES PATENT OFFICE.

OSCAR BANCROFT, OF WASHINGTON, DISTRICT OF COLUMBIA.

TYPE-WRITER ATTACHMENT.

1,088,865.

Specification of Letters Patent. Patented Mar. 3, 1914.

Application filed April 17, 1913. Serial No. 761,791.

To all whom it may concern:

Be it known that I, OSCAR BANCROFT, a citizen of the United States, residing at Washington, in the District of Columbia, have invented certain new and useful Improvements in Type-Writer Attachments, of which the following is a specification.

My invention relates to an improvement in attachments for typewriters, and the object is to provide means which will indicate or sound an alarm whereby the operator of the machine will be notified that the end of the sheet of paper being operated upon is approaching.

The invention consists in certain novel features of construction and combinations of parts which will be hereinafter fully described and pointed out in the claims.

In the accompanying drawings:—Figure 1 is a top plan view showing the invention in position with respect to an oscillating bar and platen of a typewriting machine, Fig. 2 is an end view of the apparatus shown in Fig. 1, but showing the platen in section, Fig. 3 is an end view of the device showing it in engagement with the platen, and Figs. 4 and 5 are perspective views of the device.

This invention is adapted more particularly for application to the L. C. Smith & Bros. and Monarch typewriters.

A, represents a platen which is provided with an annular groove 1. An oscillating bar B is pivotally mounted upon a shaft 2. Mounted upon the bar B is a stop 4, which has a flange 5 provided with a tapering surface 6.

A portion of the platen frame or carriage C is disclosed in Figs. 2 and 3, and on this frame is mounted a curved arm 7, the arm being pivotally connected to the frame by a link 8. Upon the lower end and on the upper side of the arm is a projection 9, which is adapted to normally enter the recess or groove 1 of the platen. Mounted upon the opposite end of the arm is a trip 10, which consists of two flanges 11 and 12 which extend at right angles to the body of the trip. The flange 11 is adapted to normally rest upon the frame C, as shown in Fig. 3. The flange 12 is provided with a beveled or tapered surface 13.

When the device is in use, as disclosed in Figs. 1 and 2, which show the paper E passed about the roll or platen, the projection 9 is held out of the recess or groove 1 of the platen, but as soon as the end of the

sheet of paper passes the projection 9, the projection will immediately enter the annular groove, causing the trip to be brought into a position whereby it will come in contact with the stop 4, which is mounted upon the oscillating bar B. The beveled surface 13 will permit the arm 7 to pass the stop in one direction, but will cause the projection 9 to be moved from the recess. When the arm 65 is moving in the opposite direction, the trip 10 will come in contact with the stop 4 again, and the flange 12 will engage the beveled surface 6 of the stop, causing the bar B to be raised. The oscillation of this 70 bar operates a bell 14, which is customary in this type of machine, thereby notifying the operator that the end of the sheet is approaching, and indicating to the operator that care should be taken in the operation 75 of the machine to prevent writing too near the lower edge of the sheet. Often the rollers which carry the paper after the paper leaves the feed-rollers, are not sufficiently strong to hold a sheet rigid, and when an 80 operator endeavors to write along the lower edge or portion of the sheet the alinement is often destroyed, because the small rollers allow the paper to shift or move upon the platen. The operator is notified that the 85 end of the sheet of paper being operated upon is approaching upon the sounding of the bell; and the bell is caused to be sounded by the mechanism only when the carriage is being moved to a position for the beginning 90 of a new line.

It will be seen that when the paper to be written upon is inserted upon the platen, that the tripping device is prevented from operating, and the projection or lug 9 is 95 held out of engagement with the annular groove; but the moment the sheet passes, the projection 9 will enter the groove causing the trip 10 on the arm 7 to be brought into engagement with the stop 4, so as to cause 100 the bell to be sounded.

The flange 11 of the trip rests upon the edge of the frame during the tripping operation, and the strain instead of being transmitted entirely to the arm 7 is taken up 105 practically, if not entirely, by the trip 10 through the flange 11 which rests upon the frame C as shown in Fig. 3.

Having fully described my invention, what I claim as new and desire to secure by 110 Letters Patent, is:—

1. The combination with a carriage-frame

- and platen having an annular groove there-
in, of an oscillating bar having a stop there-
on, an arm pivotally mounted upon the car-
riage-frame, a projection on the arm adapt-
ed to enter the annular groove of the platen,
and a trip on the arm adapted to be brought
into engagement with the stop on the oscil-
lating bar for actuating the bar upon the en-
trance of the projection in the groove.
- 10 2. The combination with a carriage,
platen and a movable bar, said platen hav-
ing the paper to be operated upon traveling
thereover, an alarm adapted to be operated

upon the movement of the bar, of an arm
pivotally mounted upon the carriage in em- 15
gagement with the paper, a stop on the bar,
and a trip upon the arm adapted to engage
the stop as the arm is released by the paper
passing out of engagement therewith for ac-
tuating the bar to give an alarm. 20

In testimony whereof I affix my signature,
in the presence of two witnesses.

OSCAR BANCROFT.
